[57] CLAIM

The ornamental design for a cabinet for electrical wave generator and monitor for physical therapy, as shown and described.

DESCRIPTION

FIG. 1 is a perspective view especially showing the front, top and one side of my new design for a cabinet for electrical wave generator and monitor for physical therapy; and

FIG. 2 is a perspective view especially showing the bottom, the rear and the other side of the cabinet design of FIG. 1 on a reduced scale.

U.S. Patent
